Primary Examiner — Messina L Smith*Assistant Examiner* — Elizabeth Borsetti(74) Attorney, Agent, or Firm — Hemisphere Law, PLLC;
Zhigang Ma(57) CLAIM

The ornamental design for an orthodontic flosser, as shown and described.

DESCRIPTION

FIG. 1 is a perspective view of an orthodontic flosser showing my new design;

FIG. 2 is a front view thereof;

FIG. 3 is a back view thereof;

FIG. 4 is a left side view thereof;

FIG. 5 is a right side view thereof;

FIG. 6 is an enlarged top plan view thereof; and,

FIG. 7 is an enlarged bottom plan view thereof.

The Fremouth TM forming part of the claimed design is a registered trademark of Tang Fanwei (INDVIDUAL; CHINA).
